ILLUMINATED CLOCK DIAL

Edgar L. Boeck, Hudson Heights, N. J.

Application March 9, 1944, Serial No. 525,737

1 Claim. (Cl. 58—50)

1

This invention relates to an illuminated clock dial or the equivalent and it aims to provide for the illumination by novel means utilizing acrylic or methyl-methacrylate plastic, commonly known as "Lucite" or "Flexiglas."

It is particularly aimed to provide a structure wherein indications of the clock dial are represented by pegs of the aforesaid "Lucite" and wherein the hands of the clock are of "Lucite" and by novel means illuminated from the same source as the pegs.

Further, an aim is to provide a ring mounting the pegs and part which illuminates the clock hands, which is made of "Lucite" which coacts directly with the illuminating means.

The more specific objects and advantages will become apparent from a consideration of the description following taken in connection with accompanying drawings illustrating an operative embodiment.

In said drawings:

Figure 1 is a view of the improved structure in front elevation;

Figure 2 is a vertical sectional view taken on the line 2—2 of Figure 1;

Figure 3 is a vertical section taken at a right angle to Figure 2 and on the line 3—3 of Figure 2;

Figure 4 is a plan view;

Figure 5 is a detail section taken on the line 5—5 of Figure 3;

Figure 6 is an elevation of the "Lucite" ring and pegs thereof;

Figure 7 is a fragmentary front elevation of the "Lucite" ring and a peg of modified form; and

Figure 8 is a perspective view of a fragment of the ring and peg of a further modified form.

Referring specifically to the drawings wherein like reference characters designate like or similar parts, I provide a ring at 10 having pegs 11 extending forwardly therefrom to indicate from one to twelve as in the case of an ordinary clock. This ring 10 and pegs 11, which may be integral with the ring or separate therefrom and attached thereto, as preferred, are adapted to be made of "Lucite." Such parts 10 and 11 are embedded or mounted in a shell generally designated 12, with the pegs 11 projecting forwardly preferably slightly beyond the front of the shell. Such shell may be mounted on or constitute part of a base or other support at 13.

At the rear of the shell, it has a recess or cavity 14 in which any standard clock works 15 is operatively mounted.

Movable over the exposed ends of the pegs 11 are minute and hour hands 16 and 17 both of the "Lucite" which are operatively attached to the minute and hour-hand operating shafts 18 and 19, respectively, of the clock works 15.

2

The shell 12 and support 13 may be made of any suitable material for instance, of wood, metal or plastic, or any combination of them, but preferably being finished in a color darker than the "Lucite" in order to contrast therewith.

It will be noted that a generally L-shaped strip 20 is also inserted in the shell 12, being integral with or attached to the ring 10 and being of "Lucite," such strip 20 terminating in a head 21 which is open at the outer face of the shell 12 directly behind and in line with portions of the hands 16 and 17.

The clock works 15 are preferably electrically operable and from the same source of energy therefor, an electric lamp 20 is energized. This lamp is accommodated in a cavity or space 21 at the back of the base 13 and is relatively close to and directly under an arcuate edge portion 22 of ring 10.

As a result, with the lamp 20 in illuminated condition, the light will pass through the ring 10 and then to the exposed ends of the pegs 11 and head 21, whereby the ends of the pegs and the end of the head 21, and hands 16 and 17 will be illuminated.

Various changes may be resorted to provided they fall within the spirit and scope of the invention. For instance, as shown in Figure 7, the free ends of the pegs 11 may be provided with numerals corresponding to the hours represented by such pegs about the clock dial.

Also, as shown in Figure 8, where the ring is designated 10a and is made of "Lucite" like the preceding rings, the pegs here designated 11a and also of "Lucite," are preferably in the form of numerals in cross section or at least at their outer ends, the numerals corresponding to the occurrence of the hours and their indications about the dial of a clock or timepiece.

I claim as my invention:

A structure of the class described comprising a ring, pegs extending from the ring, and arranged in clock-dial formation, clock works, an hour hand and a minute hand of "Lucite" carried by the hour-hand and minute-hand operating shaft of said clock works, respectively, said ring and pegs being of "Lucite," a strip of "Lucite" extending from the ring and terminating behind and in line with said hands, and illuminating means adjacent an edge portion of the ring, a shell mounting the ring and pegs, said shell having a cavity in which the clock works are disposed, supporting means for the shell, and said supporting means having the illuminating means therein.

EDGAR L. BOECK.
